UNITED STATES PATENT OFFICE.

FRANK ROSE, OF IPAVA, ILLINOIS.

NECKTIE-RETAINER.

1,260,456.

Specification of Letters Patent. Patented Mar. 26, 1918.

Application filed May 26, 1917. Serial No. 171,119.

To all whom it may concern:

Be it known that I, FRANK ROSE, a citizen of the United States, residing at Ipava, in the county of Fulton and State of Illinois, have invented certain new and useful Improvements in Necktie - Retainers, of which the following is a specification.

This invention has for an aim to provide a means for supporting cravats and neckties in proper position upon a collar, without requiring the ties to be tightly tied upon the neck of the wearer. In the use of the ordinary four-in-hand ties, for instance, it is usually necessary to draw the tie up on the collar so tightly that the neck of the wearer is often uncomfortable, in order to prevent the tie from setting so far down upon the collar as to give an untidy effect. It is an aim of the invention therefore, to give a simple construction of support for such ties, as well as various other forms of ties, which will hold them in proper position upon the collar without requiring to be drawn up tight. An important aim is to give such a device which may be supported upon the collar button. A further aim is to enable the formation of such a device from wire in an extremely small and cheap form, whereby it will be inconspicuous, light and durable.

A further aim is to give such an appliance which may be quickly attached to or removed from the collar button without necessitating the disengagement of the collar button from the collar or neck band of the wearer.

Additional objects, advantages and features of invention will appear from the disclosure herein of one of the possible embodiments of the invention, in the illustrations of which,

Figure 1 is a perspective view of a collar as worn, having my invention applied thereto,

Fig. 2 is a detail perspective view of my invention detached,

Fig. 3 is a side elevation thereof,

Fig. 4 is a front elevation thereof,

Fig. 5 is a sectional view of a collar having the invention applied thereto,

Fig. 6 is a detail view of one of the points of the device.

There is illustrated a collar 10 which may be of any of the usual forms adapted to be secured upon the neck of the wearer by means of a collar button 11 engaged through the collar band 12 of a shirt, as

illustrated in Figs. 1 and 5. A tie 13 is indicated in dotted lines in Figs. 1 and 5, in the usual position in which it is desired to maintain ordinarily, being supported so by 60 means of a holder 14 comprising my invention. In the present instance, the holder is formed from wire of suitable thickness, in practice being number 16 B. & S. gage hard steel wire, in order that the device may hold 65 a sharp point satisfactorily, and also be resilient in the desired degree. It is ordinarily formed from a small section of the wire in the neighborhood of one inch in length, bent at its middle portion into a partly circular eye portion 15, the outer parts then being recurved and extended divergently from each other as at 16, the proximal side portion of the wire lying in close spaced relation to form a throat passage 17 through 70 which the stem of a collar button may readily pass when presented between the outer parts of the wire and forced inwardly toward the eye 15. A short distance from the throat the end portions of the wire are 75 extended in parallel relation and bent outwardly in a common direction to form parallel hooks 18, the points 19 of which extend outwardly from the device approximately at an angle of 45 degrees to the plane of 80 the portions 15 and 16. The outwardly turned portions of the hooks begin preferably very close to the throat 17, so that the outer parts 19 of the wire immediately adjacent the throat comprise the shanks of 85 the hooks, and in this way it is made possible to locate the hook members very close to the head 20 of the collar button at the outer side.

The device may be made larger or smaller 95 than the proportions indicated as found desirable, to accommodate it to the uses intended, and various other changes may be made within the scope of the invention, as will be understood. It is thought desirable 100 to form the points of the pins as illustrated in detail in Fig. 6, in which the material of the wire at its extremities is represented as having been flattened and the points formed by suitably cutting the wire on lines diverging 105 from the end of the wire inwardly, so as to form a spear-like head 21 which, is of a sufficiently small size so that it may be readily forced into the fabric of a tie without damage thereto and yet owing to its 110 peculiar shape will tend to hold its place in the fabric and prevent casual disengage-

ment of a tie therefrom. By cutting the edges 22 of the point close to the point of beginning of the flattening of the wire, and by flattening the wire over but a short distance, the flat surfaces diverging inwardly, the necessary transverse enlargement of the head is obtained.

In the formation of the device it is of course desirable to form the points before 10 the bending of the wire to the form otherwise described.

In use, the collar is secured upon the neck of the wearer in the customary manner, the collar buttons 11 and 11' being adjusted in 15 place at the front and back. The support 14 is then presented over the button 11, with the eye portion 15 at the upper part, and moved downwardly, the hook element 18 being passed upon opposite sides of the 20 head 20 of the button, and the back side of the support being held flatly against the collar so that the portion 16 will engage beneath the head 20 and the stem of the button passed into the throat 17. The throat 17 is 25 preferably smaller than the stem, so that some force is required to press the device into final position with the stem of the button engaged in the eye 15, into which position it will pass as soon as the portion 16 30 passes beyond the center of the button. The device will thus be held yieldably against detachment with sufficient force to prevent its accidental disengagement. The necktie 13 which may have been previously adjusted 35 under the collar as usual, in case a turn-

down collar is employed, is tied in any of the customary knots, and the knot, after being adjusted centrally of the front part of the collar is moved slightly above the final position in which it is desired to retain it, 40 and then pressed inwardly toward the neck of the wearer and moved downwardly until the points 18 properly engage in the fabric of the tie, which will then be supported whether the knot becomes loosened or not, 45

It will be seen that a very simple and efficient device for the purposes intended is provided, and liable in a minimum degree to derangement, and adapted to be manipulated readily. 50

What is claimed:

A device of the character described, comprising a portion of wire having a central portion bent into partly annular shape to form an eye, and having its end portions bent divergently therefrom to form a throat opening into the eye, the outer end portions of the wire being bent outwardly in a common direction, being flattened over a limited distance to form lateral enlargements, 55 and being cut to form points in the outer parts of the enlarged portions for the purposes described. 60

In testimony whereof I have affixed my signature in presence of two witnesses.

FRANK ROSE.
